(57) **CLAIM**

The ornamental design for a storage system, as shown and described.

DESCRIPTION

FIG. 1 is a perspective view of a storage system, showing my new design in an open configuration in use condition; FIG. 2 is a front plan view of the storage system;

FIG. 3 is a front plan view of a component of the storage system shown separately for clarity of illustration;

FIG. 4 is a side view of the component of the storage system shown in FIG. 3, the other side being a minor image thereof;

FIG. 5 is another perspective view of the component of the storage system shown in FIGS. 2 and 3 for clarity of illustration;

FIG. 6 is another view of the component of the storage system shown in FIGS. 2-4 shown in an alternate position;

FIG. 7 is a perspective view of the storage system shown in an alternate position; and,

FIG. 8 is a perspective view of the storage system in a closed configuration.

The bed form shown in broken lines in FIG. 1 illustrates the storage system while in use and forms no part of the claimed design.

The series of dashed lines on the storage system in FIGS. 1-8 represent stitching.
